UNITED STATES PATENT OFFICE.

ISAAC H. VENN, OF YONKERS, NEW YORK, ASSIGNOR TO THE OTIS ELEVATOR COMPANY, OF SAME PLACE.

MEANS FOR CONVERTING ROTARY INTO RECIPROCATING MOTION.

SPECIFICATION forming part of Letters Patent No. 657,842, dated September 11, 1900.

Application filed October 21, 1899. Serial No. 734,353. (No model.)

To all whom it may concern:

Be it known that I, ISAAC H. VENN, a citizen of the United States, residing at Yonkers, Westchester county, State of New York, have 5 invented certain new and useful Improvements in Means for Converting Rotary into Reciprocating Motion, of which the following is a specification.

The object of my invention is to convert a 10 continuous rotary into a reciprocating motion capable of being varied in extent; and to this end my invention consists in the combination, with two driven wheels and a cable engaging said wheels and formed into loops, of 15 blocks engaged by said loops and connected with the object to be moved, and a single drive-wheel engaging said driven wheels and capable of being adjusted to vary the relative speed of the driven wheels, as fully set 20 forth hereinafter and as illustrated in the accompanying drawings, in which—

Figure 1 is a plan view illustrating one form 25 of my improved mechanical movement. Fig. 2 is a side elevation of the driving devices; Figs. 3 and 4, diagrams illustrating the arrangement of drive-cable and different arrangements of the blocks.

The part to be moved, as a wheel I, Fig. 3, or a lever I', Fig. 4, is operated by the reciprocation of two blocks B B', deriving their 30 movements from a single motor or engine M. The engine is provided with two driven wheels A A', which are positively driven in reverse direction from a single shaft *a* in such 35 manner that the respective rates of revolution of the driven wheels may be varied as desired. Around the wheels A A' and around the pulleys of the blocks B B' passes a continuous cable C, the cable being formed into 40 loops, passing from the wheel A to the block B, thence beneath the wheel A' and to the block B', and thence down to the wheel A, so that it will travel with the reversely-turning drive-wheels and pass from one to the other. 45 So long as the drive-wheels turn at the same rate of speed the cable C travels through the blocks B B', merely turning the pulleys thereof; but if one of the drive-wheels—say the wheel A'—turns at a greater speed than the 50 other the cable will be drawn from the wheel A and paid out from the wheel A', so that the

block B will be drawn downward and the draft on the block B' will be relaxed and the latter block will rise. If the superior speed is imparted to the wheel A, the action and 55 effect will be reversed.

One means of securing the direct driving of both drive-wheels from a single motor consists in providing the motor with a drive-wheel D, arranged between the wheels A A' 60 and frictionally engaging both to turn them in opposite directions. As shown, the wheels A A' are parallel, turning about a prolongation of the same axis, and each is provided at its inner side with an annular groove or depression, the faces *w* of which in cross-section coincide with the arc of a circle. The face of the drive-wheel D coincides with the face *w*, and the center of the wheel D is concentric with the center of the circle, which coincides with the opposite faces *w*. It therefore follows that when the wheel D bears at the center of each face *w*, as shown in Fig. 1, the wheels A A' will be driven at the same speed; but if the wheel D is turned so as to bear near 75 the inner edge of the groove of one driven wheel—say the wheel A—and near the outer edge of the groove of the other wheel then the wheel A will increase in speed and the wheel A' will decrease in speed. If the wheel 80 D is swung to the opposite direction, the wheel A' will be increased in speed and the speed of the wheel A will be decreased. It will be evident that this change in the relative speeds of the two wheels A A' is effected 85 without any jars or sudden changes or the cessation of or interference with the motion of the wheels or the wheel D and that the speed of the wheel D may be constant and uniform during the movements of the blocks. 90

The wheel D may be driven from any suitable motor through the intervention of any suitable flexible gearing; but, as shown, the wheel D is on a shaft *a*, having its bearings upon a frame E, carrying a motor M, the said 95 frame swinging on a pivot *s*, the axis of which is concentric with the circle coinciding with the opposite faces *w w*.

In order to insure frictional adhesion of the driving and driven surfaces, I provide bearings for the outer faces of the wheels A A' in the shape of rollers P P, turning on studs on

supports G G, pivoted to the base at their lower ends and connected by a bolt f, by tightening the nut on which the supports, with their rollers, may be drawn together to cause

5 the wheels A A' to bear more firmly on the drive-pulley. Any other suitable adjusting devices for shifting the rollers may be used.

To avoid drag or slippage of any part of the roller-bearing faces, the latter are beveled or 10 conical, as shown, and are adapted to corresponding annular and beveled bearing-faces u on the outer sides of the wheels A A'. I thus prevent the slippage and wear which would result if the faces of the rollers and of 15 the wheels A A' were flat.

As indicated, the motor M is an electric motor, and the frame E carries a shaft with a pinion b, engaging a curved rack d, the pinion b being turned in any suitable way from 20 which to shift the motor in either direction to any desired extent. Any other suitable means of adjusting the position of the drive-pulley may, however, be employed.

Without limiting myself to the constructions shown, I claim—

25 1. In an apparatus for converting rotary into reciprocating motion, the combination of a continuously-rotating drive-wheel, two driven wheels having inner annular bearing-faces transversely curved, means for changing the angle of the drive-wheel to said wheels, a cable passing around the wheels and formed into loops and blocks engaging said loops and connected to the object to be moved, substantially as set forth.

30 2. The combination of two wheels A A', an endless cable passing around each wheel and forming two loops, a block in each loop, and

a motor provided with a drive-wheel engaging both wheels A A' and adjustable to bear on the 40 wheels at different distances from the centers thereof, substantially as set forth.

3. The combination with two wheels A A' having annular bearing-faces curved in cross-section, of a drive-wheel D adjustable between said faces, two blocks, and a cable engaging said wheels A A' and formed into loops passing through said blocks, substantially as set forth.

4. The combination of the blocks, cable C, 45 two driven wheels provided with annular inner faces transversely curved, a drive-wheel D between said faces, and means for shifting the wheel D to carry its bearing-points to or from the axes of the wheels, substantially as 50 set forth.

5. The combination with the driven wheels having annular beveled faces and an intermediate drive-wheel, of roller-bearings having conical faces bearing against said beveled 55 faces, substantially as set forth.

6. The combination with the driven wheels having annular beveled faces and an intermediate drive-wheel, of roller-bearings having conical faces, and means for varying the 60 pressure of the rollers against the said beveled faces of the wheels, substantially as set forth.

In testimony whereof I have signed my name to this specification in the presence of 70 two subscribing witnesses.

ISAAC H. VENN.
